UNITED STATES PATENT OFFICE

2,449,894

LUBRICATOR DISTRIBUTOR

James J. Hennessy, Montclair, N. J.

Application October 17, 1945, Serial No. 622,866

8 Claims. (Cl. 308—85)

1

The invention relates to railway journal lubricators of the type which utilize the longitudinal motion of the journal in the journal box to actuate a mechanical pump to supply lubricant from a reservoir at the bottom of the box to the journal, preferably through a distributor adapted to spread the lubricant over a substantial area of the journal.

The structure embodying this invention includes some features described and claimed in Patent No. 2,260,520, issued to the present applicant October 28, 1941.

One object of the present invention is to facilitate the application and removal of a distributor unit, extending substantially the full length of the journal, when the space between the journal and the adjacent journal box wall and pump members is restricted as is the case with an assembled A. A. R. journal and box.

A more particular object of the invention is to facilitate replacement of the wipe pads on the lubricator after removal of the lubricator from the journal to prolong the useful life of the unit and, preferably, so that the same unit with new pads can be reinstalled on the journal in only a few minutes, thus avoiding shipment of the unit to shop and the necessity of a large number of units to maintain service.

These and other detail objects of the invention which will appear from the following description are attained by the structure illustrated in the accompanying drawings, in which—

Figure 1 is a horizontal section through a railway journal box showing the journal in broken lines and fitted with a lubricating device embodying the present invention.

Figure 2 is a longitudinal vertical section on line 2—2 of Figure 1 through the lower part of the journal box.

Figure 3 is a detail transverse vertical section on line 3—3 of Figure 2 showing the arrangement of the wipe pads.

The journal box 1, and axle 2 with journal 3 are of the usual construction and require no detail description. The mechanical lubricator consists essentially of two units, a pump 4 and a distributor 5. The pump may be as disclosed in Patent No. 2,272,199, issued to the present applicant February 10, 1942, and comprises a reciprocating piston 6 actuated through a lever 7 by the play of the axle and journal longitudinally of the box to draw oil from the bottom of the box into a cylinder in the pump body 8 from which it is discharged through a passageway 9 to a cup-like recess in which there is seated the spherical lower

5

end 10 of an arm 11 of the distributor device. Arm 11 is pivoted at 12 to depending hinge butt elements 13 on the upwardly facing concave plate 14. A lubricant passage 19 extends through elements 9, 11, 12, and elements 13 to the upper face of plate 14. Connected pivotally to one end at the upper portion of plate 14 by hinges 15 is a companion plate 16 and both plates 14 and 16 have upstanding ribs 17 at their ends disposed to engage the surface of the journal. Pivotal movement of the sections relative to each other outwardly away from the journal is limited by adjacent ends thereof abutting each other, as shown at 18, when the sections are in substantial alignment longitudinally of the journal. A spring 20 thrusts plate 14 and the swinging end of arm 11 away from each other whereby plates 14 and 16 are held against the journal and are pivotally supported by element 10 on member 8.

Hinged to the upper outer end of each plate 14 and 16 is a shallow pan 21 adapted to receive a felt pad 34 having an arcuate upper face for engaging the journal. Each pan 21 has a bottom wall 22, cut away at 23 for the purpose described hereinafter, side walls 24, and end walls 25 inclined upwardly from the bottom wall and terminating in inturned lips 26. When plates 14 and 16 and pan 21 are in substantial longitudinal alignment, pivotal movement of the pans outwardly away from the journal is limited by side walls 24 of the left-hand and right-hand pans engaging below their hinge axes, respectively, spring 20 on arm 11, and bracket 32 attached to plate 16. This arrangement causes pads 34 to be pressed against the journal, together with plates 14 and 16 by spring 20.

Each pad 34 may be made of one or more layers of felt positioned side by side and held together by a channel frame 27 having openings 28 therein to receive tongues 29 on some of the pads which fit through cut out portions 23 of pans 21. Each pad 34 has its end faces 35 inclined similar to the end walls 25 of pan 21 and these faces are recessed at 30 to receive lips 26 narrower than the recesses to permit movement of the pads in the pans in a direction radially of the journal. A spring 31, attached to the bottom wall 22 of each pan 21 by a rivet 36, is compressed between the lower face of each channel frame 27 and bottom wall 22 of each pan 21 and urges pads 34 yieldingly against the journal, in addition to the pressure exerted on pads 34, and plates 14 and 16, by spring 20. Movement of pads 34 in pans 21 in a direction radially of the journal is limited, when the distributor is removed from the jour-

30

35

nal, by lips 26 engaging pads 34 at the inner boundaries 33 of recesses 30.

Pads 34 are saturated with oil which travels longitudinally of the journal beyond the ends of plates 14 and 16 and also with oil which is lifted by capillary attraction from the bottom of the box. They provide for the wiping of surplus oil from the lead portions of the journal or for the distribution of oil to the end portions of the journal as may be required.

The hinging of pans 21 and plates 14 and 16 and the yielding nature of the arm 11 toward plate 14 facilitates the insertion of the distributor through the space between the end of the journal and the bottom wall of the journal box and the upwardly curved end wall. While spring 20 is adequate to hold the distributor elements against the journal, it is readily compressed between the fingers and thumbs of workmen when the distributor is to be inserted or removed to and from its functioning position. In practice, distributor 5 will be inserted beneath the journal before pump 4 is applied and, in the event of replacement, the pump will be removed before the distributor is removed.

If the bearing becomes overheated because defective, or for any other cause, the felt pads will char, and smoke discharged from the box will attract attention to the box so that the cause of the overheating may be remedied. The pads are readily replaceable, only a few minutes being required for the operation. To remove a pad 34 from a pan 21, the pump and distributor are removed from the journal, then the portion of pad adjacent a recess 30 protruding from the pan is pressed inwardly in a direction substantially parallel to lip 26, whereby the inner boundary 33 of recess 30 clears lip 26, and the pad and frame 27 are lifted from the pan. A new pad may be inserted in the frame and these may be reinstalled in the pan by reversing the procedure outlined above. The lubricator then is ready to be installed on the journal. To make repairs of this nature requires no tools and it is necessary, for emergency repairs, to carry replacement pads only instead of an entire distributor.

These elements and other elements of the invention may be varied and some features omitted entirely without affecting the essential features of the device, and the exclusive use of those modifications which come within the spirit of the claims is contemplated.

What is claimed is:

1. In a distributor device for a journal lubricator of the class described, a pan-like member having an upper face arranged to be opposed to a journal and receive and retain a quantity of lubricant and formed of two sections hinged at their adjacent ends and provided with elements arranged to abut each other as the sections swing about their hinge away from said face to limit the extent of such movement, a device for supporting said member from an underlying part of the lubricator, individual springs separately mounted in said sections, and pads of absorbent material supported in said sections by said springs.

2. In a distributor device for a journal lubricator of the class described, a pan-like member having an upper face arranged to be opposed to a journal and receive and retain a quantity of lubricant and formed of two sections hinged at their adjacent ends and provided with elements arranged to abut each other as the sections swing about their hinge away from said face to limit

the extent of such movement, a device for supporting said member from an underlying part of the lubricator, individual springs separately mounted in said sections, and pads of absorbent material supported in said sections by said springs, said springs and pads being supported solely by said sections.

3. In a distributor device for a journal lubricator of the class described, a pan-like member, a pad of absorbent material in said member and having a face arranged for application to a journal, the face of said pad opposite said journal engaging face normally being spaced from an opposing wall of said member, a yielding mounting in said member urging said pad outwardly thereof, and said pad and said member having interengaging elements limiting movement of said pad outwardly of said member.

4. In a distributor device for a journal lubricator of the class described, a pan-like member, a pad of absorbent material in said member and having an upper face arranged for application to a journal, the lower face of said pad normally being spaced from the bottom of said member, and a spring seated on the bottom of said member and the lower face of said pad and urging said pad upwardly of said member, said pad and said member having interengaging elements providing for limited movement of said pad upwardly and downwardly of said member.

5. In a distributor device for a journal lubricator of the class described, a pan-like member having a wall with an inturned lip, a pad of absorbent material in said member and having a face arranged for application to a journal, a yielding mounting in said member for said pad, said pad having a lateral recess to receive said lip, said recess being deeper than said lip and the face of said pad opposite its journal engaging face normally being spaced from said member to permit movement of said pad inwardly and outwardly of said member.

6. In a distributor device for a journal lubricator of the class described, a pan-like member having an inturned lip, a pad of absorbent material in said member and having a face arranged for application to a journal, said pad having a recess to receive said lip, said recess being deeper than said lip, a spring yieldingly engaging the face of said pad opposite the journal engaging face and holding the pad spaced from the bottom of said member to permit movement of said pad inwardly and outwardly of said member, said lip engaging a boundary of said recess to limit movement of said pad outwardly of said member when the distributor is removed from the journal to which it is assembled, and said pad being readily distortable adjacent said recess to free said pad from said lip to facilitate its application and removal from said extension.

7. In a distributor device for a journal lubricator of the class described, a pan-like member having an upper face arranged for application to a journal, a pan-like extension at an end of said member and hinged thereto and provided with inturned lips, a pad of absorbent material yieldingly mounted in said extension for limited movement therein and having an upper face arranged for application to the journal, a channel-shaped frame receiving said pad, a spring compressed between the bottom of said extension and engaging the lower face of said frame and urging said frame and pad yieldingly upwardly in said extension, said pad having inclined end faces provided with recesses to receive said lips, said recesses

being spaced from the bottom of said pad a distance less than the distance of said lips from the bottom of said extension to permit movement of said pad upwardly and downwardly in said extension.

8. A distributor device as described in claim 6 wherein the pad is made of several layers of felt and some layers having substantially parallel ears extending from the bottom faces thereof and which fit snugly in openings in the frame.
